CLAIM

The ornamental design for a handle for a screwdriver, as shown and described.

DESCRIPTION

FIG. 1 is a perspective view from the rear and left side of a handle for a screwdriver and the like, showing my new design;

FIG. 2 is a left side elevational view thereof, the right side view being a mirror image thereof;

FIG. 3 is a bottom view thereof;

FIG. 4 is a top view thereof;

FIG. 5 is a rear view thereof; and,

FIG. 6 is a front view thereof.

The broken line showing of the bit is for illustrative purposes only and forms no part of the claimed design.

FIG. 1

FIG. 2

FIG. 3

FIG. 4

FIG. 5

FIG. 6
